UNITED STATES PATENT OFFICE.

FRANK MILLER SPARROW, OF MATTAPoisETT, MASSACHUSETTS, ASSIGNOR.
BY MESNE ASSIGNMENTS, TO HIMSELF AND WILLIAM E. SPARROW, OF
SAME PLACE.

ELECTRIC HOT-AIR-FURNACE REGULATOR.

SPECIFICATION forming part of Letters Patent No. 295,686, dated March 25, 1884.

Application filed June 13, 1883. (No model.)

To all whom it may concern:

Be it known that I, FRANK MILLER SPARROW, of Mattapoisett, in the county of Plymouth, of the Commonwealth of Massachusetts, have invented a new and useful Improvement in Electric Hot-Air-Furnace Regulators; and I do hereby declare the same to be described in the following specification and represented in the accompanying drawings, of

10 which—

Figure 1 is an elevation of a hot-air furnace with my invention applied thereto. Fig. 2 is a vertical and median section, and Fig. 3 a front elevation of the ash-chamber valve and its operative magnet. Fig. 4 is a vertical and median section, and Fig. 5 a front view of the smoke-discharge-pipe valve and its operative magnet. Fig. 6 is a front view of one of the electrical switches to be described.

20 My invention is to preserve at about an equal temperature the air of an apartment warmed by an air-heating furnace. To this end I have within the apartment what is termed an ordinary "metallic thermometer"—
25 that is, one having a dial, a hand thereto, and a mechanism which, by expansion or contraction induced by changes of atmospheric temperature, will cause the hand to traverse or move relatively to the dial. In Fig. 1 such a
30 thermometer is shown at A as provided with a hand, a, arranged at one end between the metallic abutments e and f, from which wires g and h extend, respectively, to the opposite poles of a galvanic battery, B.

35 The air-heating furnace is shown at C as provided, in the usual manner, with air-distributing pipes D D and a smoke-discharge pipe, E, opening at or near its middle into an auxiliary pipe, F. To the throat of the ash-chamber of the said furnace there is a valve, G, which is shown on an enlarged scale in Figs. 2 and 3, such valve, when closed, being somewhat inclined to the horizon, and constructed so as to close by the action of gravity or by a spring. Extending across the valve, which is pivoted at or near its middle to the throat, is an armature, i, which is a common bar-magnet, and in front thereof is an electro-magnet, H, which is supported by

an arch, I, projecting from the ash-chamber throat. From the arch there extends between the two spools of the magnet an arm, k, carrying a switch, l, arranged to vibrate between two metallic abutments, m and n. From these abutments wires a and b extend, respectively, to the opposite poles of the battery. The wire of the electro-magnet is at one end attached to the switch. From the said magnet the wire extends, as shown, to the metallic pivot of the hand a of the thermometer. Furthermore, there projects from the valve a stud, p, which, on the armature being drawn up to the magnet, is carried against the switch and forces it off the abutment m and against the abutment n. The switch is a metallic spring, the inherent elasticity of which carries it into contact with the abutment m on the stud p moving away from the switch.

The smoke-discharge pipe E of the furnace is open at its outer end, and has there applied to it a valve, K, (provided with an armature, u, which is a bar-magnet,) arch L, magnet M, switch N, arm O, and abutments r s, essentially such as hereinbefore described as applied to the throat of the ash-chamber of the fire-place of the furnace. Wires c and d extend from the two abutments r and s of the switch N to the wires a and b. The wire t of the magnet M at one end connects with the switch, and is extended to and at its other end is connected to the wire o.

In the operation of the described apparatus each valve is open when the other is closed. The thermometer is to be supposed to be in the room or apartment, the atmosphere of which is to be maintained at or about a given temperature. On the temperature falling sufficiently to cause the hand of the thermometer to be carried against one of the abutments e f, an electric circuit will be closed, so as to cause the magnet M to close the valve K. In closing the valve, the stud v of it will be moved against the switch N, and will press it away from one and force it against the other of the abutments r and s, whereby the circuit of the said magnet will be broken and the armature will, by its inherent magnetic attraction, be kept up to the electro-magnet, so as to hold the valve

closed. While this takes place the magnet H becomes magnetized and attracts its armature and opens the valve G. The circuit for the magnet H then becomes broken by the action 5 of the stud *p* against the switch *l*. The armature *i*, by its inherent magnetic attraction, will be kept up to the magnet H, and will hold the valve open in order for air to rush into the throat of the ash-chamber, and thence through 10 the fire to increase combustion, and as a consequence the heat given out by the furnace. At the same time air will be stopped from entering the pipe E. On the temperature of the air in the apartment increasing sufficiently to 15 cause the thermometer-hand to be moved into contact with the other of the abutments *e* and *f*, the valve G will be closed and the valve K opened. Of course the supply of air to the ash-chamber will thereby be stopped and air 20 will enter the pipes E and F, whereby combustion of the fuel will be rendered slower.

In operating the magnets H and M, the thermometer-hand is to be supposed to be against the abutment *e*, which, by the wire *h*, is connected with the positive pole P of the battery. 25 The current then goes from the battery through the needle and its pivot, and thence through the wires *o* and *t*. At their junction the current divides, part of it flowing through one 30 and the rest through the other of the two magnets, and thence, by means of the switches, through the wires *a* and *c* to the negative pole N of the battery. When the thermometer-hand is against the abutment *e*, the valve G 35 will be opened and the valve K will be closed; but when the hand moves up to the abutment *f*, the valve G will be closed and the valve K will be opened, the current in the latter case being reverse, so as to cause the magnets to 40 repel the armatures, like poles of which will then be opposite like poles of the magnets. When the galvanic current is passing in one

direction through either of the magnets of the circuit, such magnet will attract its armature, whose north pole is then to be supposed to be 45 next the south pole of the magnet. On the current through the magnet being reversed, the poles will be changed, so as to cause the magnet to repel the armature. With each magnet, its magnetized armature, switch, circuit, 50 and battery, the magnetic current is caused to pass in one and next in the opposite direction through the magnet, and the current is only produced when the armature may be in movement either toward or away from the 55 magnet. Thus it will be seen that the battery is not in operation while the armature is at rest—an advantage which will be readily apparent to electricians.

I claim—

1. In combination with a furnace and a thermostat or thermometer, substantially as described, and with the valves G and K of the fire-place and discharge-flue of such furnace, the magnetic armatures, the two electro-magnets, the two switches, the current-wires, and battery, and abutments, as adapted and arranged substantially and to operate as set forth.

2. The combination of an electro-magnet, H, 70 a magnetized armature, *i*, therefor, a switch, *l*, and its abutments *m* and *n*, a thermostat or dial thermometer, A, as described, a battery, B, and circuit-wires *a*, *b*, *g*, *h*, and *o*, arranged and adapted substantially as represented, 75 whereby an electric current may be caused to pass in one and next in the opposite direction through the magnet, and such current be produced only when the armature is in movement relatively to the magnet.

FRANK MILLER SPARROW.
